(57) **CLAIM**

The ornamental design for a bumper for electronic communications device, as shown and described.

DESCRIPTION

FIG. 1 is a rear, left-side, and top perspective view of a bumper for electronic communications device showing our new design;

FIG. 2 is a rear elevation view of the bumper for electronic communications device of FIG. 1;

FIG. 3 is a front elevation view of the bumper for electronic communications device of FIG. 1;

FIG. 4 is right-side elevation view of the bumper for electronic communications device of FIG. 1;

FIG. 5 is a left-side elevation view of the bumper for electronic communications device of FIG. 1;

FIG. 6 is a top plan view of the bumper for electronic communications device of FIG. 1;

FIG. 7 is a bottom plan view of the bumper for electronic communications device of FIG. 1;

FIG. 8 is a front, right-side, and bottom perspective view of the bumper for electronic communications device of FIG. 1; and,

FIG. 9 is a front, right-side, and top perspective view of the bumper for electronic communications device of FIG. 1.
